DESIGN FOR A FLOWERPOT STAND

Helen Wiesenthal, Elizabeth, N. J.

Application October 18, 1934, Serial No. 53,672

Term of patent 7 years

To all whom it may concern:

Be it known that I, Helen Wiesenthal, a citizen of Germany, residing at Elizabeth, in the county of Union and State of New Jersey, have invented a new, original, and ornamental Design for a Flowerpot Stand, of which the following is a specification, reference being had to the accompanying drawing, forming part thereof.

Fig. 1 is a plan view, Fig. 2 is a front elevational view, and Fig. 3 is an end elevational view of a flowerpot stand, showing my design.

I claim:

The ornamental design for a flowerpot stand, as shown.

Signed at New York, N. Y., this 6th day of October, 1934.

HELEN WIESENTHAL.
